US0D1027388S

(12) United States Design Patent (10) Patent No.: US D1,027,388 S
(45) Date of Patent:  May 21, 2024

(54) CROP TOP

(71) Applicant: Gymshark Limited, Solihull (GB)

(72) Inventor: Isla Gilbertson, Solihull (GB)

(73) Assignee: GYMSHARK LIMITED, Solihull (GB)

() Term: 15 Years

(21) Appl. No.: 29/832,877

(22) Filed: Mar. 30, 2022

(30) Foreign Application Priority Data

Sep. 30, 2021 (GB) 6167885

(51) LOC (14) Cl. 02-02

(52) U.S. Cl. ..... USPC D2/717

(58) Field of Classification Search

USPC D2/717, 731, 728, 840, 706

CPC A41D 13/0015

See application file for complete search history.

(57) CLAIM

I claim the ornamental design for a crop top, as shown and described.

DESCRIPTION

FIG. 1 is a front perspective view of a crop top in accordance with my new design;

FIG. 2 is a rear perspective view of the crop top of FIG. 1;

FIG. 3 is a front side view of the crop top of FIG. 1;

FIG. 4 is a rear side view of the crop top of FIG. 1;

FIG. 5 is a right side view of the crop top of FIG. 1; and,

FIG. 6 is a left side view of the crop top of FIG. 1.

The broken lines in the figures depict unclaimed features that form no part of the claimed design.

1 Claim, 6 Drawing Sheets
